H. B. HARTMAN

MIXER FOR OZONE WATER PURIFYING APPARATUS

Filed Jan. 12, 1920

UNITED STATES PATENT OFFICE.

HARRY BUXTON HARTMAN, OF SCOTTDALE, PENNSYLVANIA, ASSIGNOR TO ELECTRIC WATER STERILIZER AND OZONE COMPANY, OF SCOTTDALE, PENNSYLVANIA, A CORPORATION OF PENNSYLVANIA.

MIXER FOR OZONE WATER-PURIFYING APPARATUS.

Application filed January 12, 1920. Serial No. 350,818.

To all whom it may concern:

Be it known that I, HARRY B. HARTMAN, a citizen of the United States, residing at Scottdale, in the county of Westmoreland and State of Pennsylvania, have invented certain new and useful Improvements in Mixers for Ozone Water-Purifying Apparatus, of which the following is a specification.

10 This invention relates to gas and liquid mixers, and more particularly to a device for use in connection with water purification apparatus for bringing ozone into intimate contact with the raw water.

15 Accordingly, as a primary object, the present invention contemplates a device which will thoroughly mix the oxidizing agent ozone with water in such a manner that the thorough treatment of the latter in

20 a practical and effective manner is assured. That is to say, the invention proposes to provide a device wherein the ozone, which is heavier than air, may be distributed over a maximum surface area and pocketed or 25 trapped in such a manner that the water passing through the device will be agitated or broken up while in the presence of and surrounded by the ozone.

30 A further object of the invention is to provide a mixer which may be readily taken apart and assembled, and by reason of its unit construction may be set up in any desired size to meet the capacity of the various machines with which it may be used. In 35 this connection, it is proposed to provide a mixing device which has a wide range of application from a preferred use with relatively small household machines to a use with larger machines for other purposes.

40 The construction however is especially adaptable to what is known as a household machine, wherein economy of space is necessary, without sacrificing the facilities for insuring the proper mixing of the raw water 45 and ozone.

With the above and other objects in view which will more readily appear as the nature of the invention is better understood, the same consists in the novel construction, combination and arrangement of parts hereinafter more fully described, illustrated and claimed.

A preferred and practical embodiment of

the invention is shown in the accompanying drawings, in which:—

55 Figure 1 is a vertical sectional view of the improved mixing device, the general line of section being indicated at 1—1 on Figure 2.

Figure 2 is a horizontal cross-section on the line 2—2 of Figure 1.

60 Figure 3 is a horizontal cross-section on the line 3—3 of Figure 1.

65 Similar reference numerals designate corresponding parts throughout the several figures of the drawings.

A distinctive feature of the invention is the provision of a mixing device consisting of a plurality of relatively interchangeable baffle units which are preferably assembled in pairs when in use to obtain maximum efficiency. That is to say, the present mixing device generally comprises in its organization a body portion consisting of a plurality of individual baffle units A and B, preferably of porcelain or similar material, 70 and stacked one upon the other in such a manner as to provide a sinuous or tortuous passage therethrough for the water and ozone. When the several units are assembled as shown in Figure 1 they provide in effect a 75 tubular mixing casing whose interior offers a maximum degree of resistance to fluid passage, the unit A being the initial or receiving unit and the unit B being the discharge unit. And, when the desired number of 80 units are assembled, the inlet and outlet ends of the casing may be closed by an inlet cap C and an outlet cap D respectively, each having suitable threaded nipple portions for connecting with the piping of the apparatus. 85 To facilitate the holding of the baffle units in position, the said end caps C and D may be provided with suitable ears E for receiving the tie bolts F, as shown in Figure 1.

90 As previously indicated the individual baffle units A and B are preferably made of porcelain or like material which will not become oxidized by the ozone, and as the end caps C and D are preferably of metal such as brass, it is desirable to provide the same 95 with an interior non-oxidizing lining L as shown. Thus, the mixing device is thoroughly protected against the corrosive action of the ozone while at the same time the protection afforded in this respect also maintains the standard of purity of the water by 100 105

22
reason of preventing the formation of foreign chemical substances which might otherwise result if the ozone could act on any of the parts of the mixer.

5 Referring to the baffle unit A which is preferably superposed on the unit B, it may be observed that the same is of substantially disk-like formation with a conical bottom wall 1 which constitutes a water shed 2 leading from the apex 3 of the cone to the valley or gutter 4 at the lower edge thereof. For the purpose of checking the progress of the water and also pocketing the ozone, the water shed 2 is preferably provided with a 10 plurality of spaced upstanding fins or baffles 5 and 6 which may be arranged in staggered relation and in spaced concentric series shown in Figures 1 and 3.

15 The unit A is preferably assembled adjacent the inlet cap C and the apex of its cone is substantially coaxial with the inlet of the cap whereby water and gas entering the device at this point will be dashed against the inclined surface of the water-shed and also against the baffles from whence it will make its way to the valley 4 to make 20 its exit through the grouped holes 7 provided in the floor of the valley into the unit B beneath.

25 30 The unit B is in effect a complement of the unit A and is particularly designed to bring the water and ozone from the rim toward the axis of the device so as to insure the concentration of the fluids which

35 were previously spread out or separated in the unit above to thereby cause intimate mixing as the same are discharged from one pair of units to the next wherein the process of spreading out and concentrating is

40 again repeated. Accordingly, by reference to Figures 1 and 2 of the drawings it may be observed that the baffle unit B is provided with an interior frusto-conical web or bottom portion 8, which inclines downwardly from the periphery of the rim toward the center where it is provided with a relatively large exit opening 9. The upper inclined surface of the web 8 is preferably formed with a plurality of upstanding 45 projections or fins 10 and 11 similar to the fins 5 and 6 and which constitute baffles for obstructing the progress of the fluids for the purpose previously indicated. In

50 55 In connection with the baffles 10, it may be observed that the same are arranged in such a manner that valleys or pockets 12 are formed beneath the grouped discharge openings 7 of the unit A, and the said baffle projections 10 as well as the baffles 11 are

60 arranged in spaced concentric circular rows, the baffles of one row being staggered with reference to those of the other, thereby providing maximum resistance to fluid progress, which is the end desired to insure thorough

65 mixing. Where a number of the superimposed units A and B are used in the device, the unit B discharges directly into the conical bottom web of the next succeeding lower unit A as will appear from Figure 1 of the drawings.

70 75 From the foregoing, it will be obvious that the distinctive feature of the present invention is the provision of a plurality of baffle units which may be arranged in novel relation to insure the thorough mixing of water and ozone, and by reason of the formation of the individual baffle units their multiplication in pairs or sets may be carried on to any desired degree to thereby adapt the mixing device to machines of 80 varying capacity. Furthermore, by reason of the separable character of the structure, its accessibility for adjustment and repairs is assured while at the same time the initial assembly and installation is greatly facilitated. In this connection, it may be observed that the outer surface of each unit may be provided with an index mark M for assisting in the proper assembly of the unit so that the interior baffles will properly 85 register and align when the device is set up for use.

90 95 Without further description, it is thought that the many features and advantages of the invention will be readily apparent and it will, of course, be understood that changes in the form, proportion and details of construction may be resorted to without departing from the spirit of the invention or scope 100 of the appended claims.

100 I claim:

1. A fluid mixing column comprising inlet and discharge caps, a plurality of paired baffle units clamped between said caps and each pair consisting of sections having ring-like outer walls and one of said sections having a conical inner wall having spaced upstanding staggered abutments and openings between the base of the conical inner wall and the ring-like outer wall, and the other of said sections having an inverted frusto conical interior wall providing a central opening and also having upstanding baffle walls thereon, and means for connecting the caps to hold the units in assembled 110 relation.

115 120 125 2. A tubular mixing column comprising end caps and a plurality of ring-like baffle sections arranged in stacked relation between said caps and having reversely related conical baffle walls, one of said walls being perforated near its base, and the other being truncated to provide an axial outlet.

In testimony whereof I hereunto affix my signature in the presence of a witness.

HARRY BUXTON HARTMAN
